UNITED STATES PATENT OFFICE.

JOHN H. McCORMICK, OF COLUMBUS, OHIO, AND JAMES D. MORRISON, OF WASHINGTON, DISTRICT OF COLUMBIA, ASSIGNEES, BY MESNE ASSIGNMENTS, TO THE INTERNATIONAL REGISTER COMPANY, OF COLUMBUS, OHIO, A CORPORATION OF OHIO.

CASH REGISTER AND INDICATOR.

No. 805,224.

Specification of Letters Patent.

Patented Nov. 21, 1905.

Original application filed April 5, 1895, Serial No. 544,583. Divided and this application filed September 28, 1905. Serial No. 280,549.

To all whom it may concern:

Be it known that we, JOHN H. McCORMICK, residing at Columbus, in the county of Franklin and State of Ohio, and JAMES D. MORRISON, residing at Washington, in the District of Columbia, have invented a certain new and useful Improvement in Cash Registers and Indicators, of which the following is a full, clear, and exact description, reference being had to the accompanying drawings.

Our invention relates to improvements in cash registers and indicators, the present application being a division of our application Serial No. 544,583, filed April 5, 1895, and it especially relates to that class of cash-registers in which a single keyboard is adapted to control registering devices which while operated by common actuating devices are nevertheless independent so far as the registration of amounts thereon is concerned. The particular invention illustrated and described in this divisional application, however, is capable of use with registers of different types, as will more clearly appear hereinafter.

In the machine shown in the present application the register-actuating devices are normally retained in a locked or inoperative position.

One of the objects of the invention is to provide means whereby the depression of a key in one of the vertical rows of the keyboard will release the register-actuating device corresponding with the row of keys in which said key has been depressed and retain said device in this operative condition as long as said key is held depressed.

A further object of the invention is the provision of means for retaining the keys in their depressed positions and for subsequently releasing them.

In this type of machine it is also desirable to hold the indicator-wheels in their set or indicating positions between successive operations of the machine.

A further object of the invention, therefore, is the provision of means for maintaining the indicator-wheels in the position to which they have been moved by one operation of the machine and for releasing the same when a key is depressed in the next succeeding operation of the machine.

A further object of our invention is to improve on the constructions set forth in the

patents of John H. McCormick, Nos. 570,141 and 610,365.

55

We attain these objects by the construction shown in the accompanying drawings, in which—

Figure 1 is a transverse sectional elevation of a machine embodying our invention. Fig. 60 2 is a transverse sectional elevation of the machine looking in the opposite direction, the parts being shown in their normal positions. Fig. 3 is a view similar to Fig. 2, showing the parts in their operated position; and 65 Fig. 4 is a front elevation of the machine having our invention applied thereto.

Like parts are represented by similar characters of reference in the several views of the drawings. These drawings, however, show 70 many features of our invention which are not specifically described or referred to herein, as they relate to constructions which are described and claimed in our application, Serial No. 544,583, of which the present case is a 75 division. It is not deemed necessary to specifically describe any parts in this application which do not directly relate to the features of our invention claimed herein.

The main frame, on which all of the operating devices are supported, consists, essentially, 80 of end pieces *a a*, which are connected together by a series of rods or shafts, numbered, respectively, from 1 to 8, and on which various parts of the mechanism are supported. 85 This frame is placed within a casing, but for convenience the casing has been omitted from all of the views. As in the other patents referred to, a keyboard is provided at one end of the frame, the keys thereon being arranged 90 in series, as shown at *a' a' a' a'*, each series being provided with nine keys numbered from "1" to "9," inclusive. The keys in each series are duplicates of those in the other series and all the keys are alike except in the length of 95 the stems. They each consist, essentially, of a stem *b*, having at one end a button *b'* and provided with a spring *b''* for holding the key in and returning it to its normal position. The keys of each series are all slidably mounted 100 in a curved frame *b'*, which is supported at each end on the frame-rods 2 and 1. (See Fig. 3.) Each key has a laterally-projecting pin *b'*, which projects through a slotted opening *b''* in the frame. As in the said patents 105 referred to, a swinging frame *c* is employed

opposite to the series of keys having on its periphery steps c' to contact with the respective key-stems when the same are depressed, so as to determine the movement of said frame 5 when released. The projecting pins b' on the keys are each adapted to contact with a segment plate or detent d , having beveled hook-shaped projections d' , which engage with said pins and retain them when depressed to the 10 limit of their movement. A similar but independent segment or plate d^2 is employed at the side of and adjacent to the segment d and has similar beveled projections d^3 , except that they are not hook-shaped. This segment 15 or plate d^2 , which we will term the "plain" segment, is provided with a projection d^4 , adapted to contact with one arm of a bell-crank lever d^5 , the other arm of which is provided with a hook d^6 to engage a lug or projection c^2 on the swinging frame c , the bell-crank lever being mounted on the frame-rod 2. As a key is depressed the projecting pin b' , contacting with the beveled projections on each of the segments d and d^2 , moves said 20 segments simultaneously about the rod 3, on which they are journaled. As soon as the key is depressed to its limit the segment d returns by gravity to its normal position and engages the pin or projection on the key and holds it. The segment d^2 , however, remains in the position to which it is forced by the depression of the key and by its movement oscillates the bell-crank lever d^5 sufficiently 25 to cause the hook d^6 to disengage the pin c^2 on the swinging frame c and allow it to move until it contacts with the key which is depressed. In the patents referred to a single segment d was employed for retaining the 30 keys when depressed and for releasing the swinging frame. In this application one segment retains the keys, while the other segment releases the frame, and this arrangement makes it impossible to release the frame, and thereby place the registering mechanism 35 in position for operation, until the key is engaged by the other segment d , which we term the "hook-segment."

Each of the swinging frames c has connected thereto a bar c^3 , which extends across the 40 frame and across the different series of registering devices to form intermediate actuating devices, which determine the amount to be registered, as is clearly set forth in the 45 patents referred to. The machines shown in 50 said patents, however, have means for turning the registering-wheels (shown at e in the present application) which are operated upon the closing movement of the cash-drawer. Since the devices which engage with 55 the registering-wheels for turning them form no part of our present invention, it is not deemed necessary to show or describe them in this divisional application, the same being fully described and illustrated in application 60 Serial No. 544,583, above referred to.

Surrounding the bars c^3 when in their normal positions is a U-shaped frame c^4 , the ends of which are perforated and journaled on the rod 3. This frame is provided at each end with perforated depending lugs c^5 , through 70 which is extended a rod c^6 , which connects the two ends of said frame and also passes through pivoted levers c^7 , of which there are two, one at each end of the series of registering-wheels, which are threaded on said rod 75 and constitute, in effect, a part of said frame, said levers c^7 being extended downwardly and backwardly and normally resting on rollers g , journaled in suitable frames g^2 , attached to the rear of the cash-drawer h .

The depression of a key in any series on the keyboard releases a swinging frame, to which is attached the actuating-bar c^3 , corresponding to the denomination of said series. 80

As is fully shown and described in our application Serial No. 544,583, the cash-drawer is normally held in its closed position, as shown in Figs. 1 and 2, and is released by the depression of one of a series of special keys f^4 . But one of these keys is shown in the 90 present application, and the means whereby this unlocks the drawer is not illustrated herein, as it forms no part of the present invention. Enough has been described and shown, however, to make it clear that when a key in 95 the keyboard has been depressed and followed by the depression of a key f^4 the actuating frame or frames corresponding to such series will be released and the drawer unlocked. When the drawer is thus released, 100 it will be thrown open by a suitable spring, and this will be followed by a movement of the frame c^4 and the bar or bars c^3 , which are connected to such of the graduating frames c as have been released. 105

Over each series of keys is an indicating-wheel j , having thereon a pinion j^2 , adapted to be engaged by a rack j^3 . These indicating-wheels have on their peripheries numbers corresponding to the numbers of the 110 keys on each series. The racks are connected to an arm j^4 , pivoted on the frame-rod 3 and resting normally in contact with a pin j^5 on one of the swinging frames c . Any movement of said frame therefore produces 115 a corresponding movement of the indicating-wheel, and as the movement of said frame is determined by the key which is depressed the indicating-wheel will expose a number corresponding to said key, it being understood that these indicating-wheels are inclosed in a suitable casing having an opening through 120 which the number on the indicator is displayed in the usual manner. Whenever a key is depressed and the drawer opened, therefore, the value of the key is displayed by the indicating-wheels j . Means are provided by 125 which these indicating-wheels are retained in position to show the last amount indicated thereby, even though the other parts are re- 130

turned to their normal positions, which occurs as the drawer is closed, as will be more fully described hereinafter. The indicators are retained in any position to which they 5 may be moved by a swinging plate j^5 , which is adapted to engage with ratchet-teeth j^6 on the rack-bar j^2 , which operates each of the indicating-wheels. Whenever a key is depressed, however, to register a succeeding 10 amount, all the indicators are returned to their normal positions or to zero. This is accomplished through the following mechanism, which is best shown in Fig. 1: A spur d^{21} , beveled on the end, is formed on the plain segment d^2 . The beveled end of this segment contacts with a rod or bar d^{22} on a swinging frame d^{23} , which is journaled on the same shaft j^7 that carries the swinging plate j^5 . A link d^{24} is pivoted to the frame d^{23} , having a shoulder d^{25} . This link d^{24} extends through a slotted opening j^8 in the swinging plate j^5 . (See Fig. 4.) Whenever a key is depressed in the series, the movement of the plain segment by reason of the spur d^{21} causes the frame d^{23} to oscillate, and thus withdraws the swinging plate j^5 from contact with the ratchet-teeth j^6 in the rack-bars, allowing the indicating-wheels to return to zero, which they do by reason of a spring j^9 , which connects the swinging arm j^4 with the extension of the swinging frame c . The depression of a key in any series therefore simultaneously releases all the indicators that had been set by the previous operation of the machine. Prior to the time when the drawer is opened any key on the keyboard may be depressed. The pressing of any key in one series will release any other key in that series which has been depressed by moving the hook-segment so as to release the pins on said key-stem. When the drawer is open, however, means are provided for positively locking all the keys in all the series. This is accomplished as follows: The hook-segments d are each provided with an extended leg d^{10} , having at the end a foot d^{11} . Journaled on the shaft 6 (see Figs. 1 and 2) is a vibrating frame d^{12} , connected by a link connection d^{13} to an oscillating lever d^{14} on the shaft 7. This oscillating lever d^{14} is held in a normal position by a spring d^{15} , but is capable of moving in either direction. A backwardly-extending projection h^2 on the drawer h is adapted as the drawer is opened to contact with the lower end of the oscillating lever d^{14} , and thus draw the frame d^{12} into contact with the legs d^{10} on the hook-segments d , a pivoted hook d^{16} on the rod 4 being adapted to engage the frame d^{12} and hold it in contact with said legs d^{10} , and thus positively lock the hook-segments d . The end of the link d^{13} where it connects with the oscillating lever d^{14} is adapted so that said lever is permitted to return to its normal position, while the oscillating frame d^{12} remains in contact with the legs d^{10} . As the drawer

is closed, therefore, the projection h^2 again contacts with the lever d^{14} on the opposite side and moves it in the opposite direction. Now there is journaled on the rod 4 an oscillating frame d^{17} , which has a transverse bar d^{18} extending across and under the feet d^{11} on the legs d^{10} . A link d^{19} connects the frame d^{17} to the oscillating lever d^{14} on the opposite side of the center from the connection on the link d^{13} , so that as said oscillating lever is 75 moved by the closing of the drawer the frame d^{17} is oscillated and raises the legs d^{10} , thus moving the hook-segments d out of engagement with the pins on the key-stems. The swinging hook d^{16} has an auxiliary arm d^{20} , 80 which also rests in contact with the bar d^{18} of the swinging frame d^{17} , so that the first movement of said frame causes the swinging hook d^{16} to become disengaged from the U-shaped frame d^{12} , thus unlocking the hook-segments 85 and permitting them to be moved back to disengage the keys as the drawer is closed. As soon as the projection h^2 passes the oscillating lever d^{14} all the parts assume their normal position. 90

Having thus described our invention, what we claim as new, and desire to secure by Letters Patent, is—

1. In a cash-register, a circular keyboard having a series of keys, and a registering 95 mechanism independent of but adapted to be controlled by said keys, two pivoted segments adjacent said keys, one of said segments having hook-shaped projections adapted to engage said keys when depressed, and the other 100 having beveled projections adapted to be moved by said keys so as to unlock the registering mechanism, substantially as specified.

2. In a cash-register, a circular keyboard, a series of keys thereon each having a laterally-projecting pin, a hook-segment and a plain segment pivoted so as to lie adjacent to said keys and in line with said projecting pins, a registering mechanism adapted to be controlled by said keys, a locking device for said 105 registering mechanism, and a connection from said plain segment to said locking device whereby a movement of said segment will unlock the registering mechanism while the other segment engages the projecting pin on 110 either of said keys which is depressed, substantially as specified.

3. In a cash-register, a normally locked operating member, a key, a detent-plate adapted to hold said key when depressed, a second 120 plate operated by said key, and means controlled by said second plate for unlocking the operating member when the key is depressed.

4. In a cash-register, a normally locked operating member, a key, a detent-plate, hooks 125 on said plate for engaging the key and holding the same depressed, a second detent operated by said key, and means controlled by said second detent for unlocking the operating member when the key is depressed. 130

5. In a cash-register, a shaft, a plurality of keys arranged radially with respect to said shaft, a register, an operating mechanism for said register, means for locking said operating mechanism, a hooked detent for holding the keys depressed, and a second detent operated by the keys, said second detent being pivoted on said shaft and controlling the locking means.
- 10 6. In a cash-register, a register, a bank of keys, a hooked detent-plate for holding said keys depressed, a second detent operated by said keys, a normally locked operating mechanism, a pivoted locking device for said mechanism, and connections between said second detent and said locking device whereby, when a key in the bank is depressed, the said second detent will rock the locking device and release the operating mechanism.
- 15 7. In a cash-register, a shaft, a plurality of keys arranged radially with respect to said shaft, a register, an operating mechanism for said register, means for locking said operating mechanism, a detent-plate having hooks for engaging and holding the depressed keys, said plate having its edge with the hooks curved with the shaft as a center, a second detent pivoted on said shaft and adapted to be operated by the keys when they are depressed, and connections between said second detent and the locking means for the operating mechanism, whereby said operating mechanism is unlocked when the key is depressed.
- 20 8. In a cash-register, a register, a bank of keys, a hooked detent-plate for holding said keys depressed, a second detent operated by said keys, a normally locked operating mechanism, a pivoted device for locking said mechanism, and a pin or lug projecting from said second detent and adapted by contact with said locking device to rock the latter and unlock the operating mechanism.
- 25 9. In a cash-register, a register, a normally locked operating mechanism therefor, a bank of keys, a hooked segment-plate for holding said keys depressed, a second plate operated by said keys, a pivoted device for locking said operating mechanism, said device being provided with a hook for engaging a part of said mechanism, and connections between the said second plate and the pivoted device whereby the latter is rocked to disengage its hook from the operating mechanism when a key in the bank is depressed.
- 30 10. In a cash-register, a register, a normally locked operating mechanism therefor, a bank of keys, a hooked segment-plate for holding said keys depressed, a second plate operated by said keys, a pivoted device for locking said operating mechanism, said device being provided with a hook for engaging a part of said mechanism, and a pin or lug projecting from said second plate and adapted by contact with said pivoted device to rock the latter, whereby when a key in the bank is depressed the said device will be rocked and its hook disengaged from the operating mechanism.
- 35 11. In a cash-register, a register, a bank of keys, a hooked segment-plate for holding said keys depressed, a second plate operated by said keys, a normally locked operating mechanism, a pivoted device for locking said mechanism, a pin or lug projecting from said second plate and adapted by contact with said locking device to rock the latter and unlock the operating mechanism, said second plate and depressed key being adapted to hold the locking device in its unlocked position until the key is released.
- 40 12. In a cash-register, a plurality of keys, a normally locked operating mechanism, a hooked plate for retaining the keys when depressed, a second plate adapted to be moved by the keys, means operated by said second plate for unlocking the operating mechanism, and means for positively locking the hooked plate after the operating mechanism has been moved from normal position.
- 45 13. A keyboard having a series of keys adapted to be moved longitudinally, a lateral projection on each of said keys, and a pivoted segment having beveled teeth on its periphery in line with said projections, an indicator corresponding to said key, said indicator being normally held in operated position, a connection from said segment to the holding device of said indicator, and means as described for releasing the indicators corresponding to the other keys by a movement of said segment, substantially as specified.
- 50 14. A keyboard having a series of keys, a rotating indicator having numbers corresponding to the numbers on said keys and controlled by same, a normally locked actuating device adapted by its movement to operate said indicator, means for releasing the lock of said actuating device, a retaining - lever to hold said indicator in any position to which it may be moved by said actuating device and means actuated by said keys for releasing said indicator, substantially as specified.
- 55 15. A series of keys, and a pivoted vibrating segment adapted to be moved by the depression of either of said keys, an indicating-wheel having numbers corresponding to the numbers on said keys, and a rack for operating said indicating-wheel, and actuating devices controlled by said keys to cause said indicating-wheel to move to a predetermined position after a key has been depressed, a retaining-lever to engage with said rack and hold the indicator after the actuating device has returned to its normal position, and a connection from said pivoted vibrating segment to said retaining-lever whereby a succeeding movement of said segment releases said indicator, substantially as specified.
- 60 16. In a registering-machine, a key, a plate having a beveled tooth for engagement by said key, an indicator having a number corre-

sponding to the number on the key, a normally locked actuating device adapted by its movement to operate said indicator, a connection from said plate to the lock of said actuating device, a retaining-lever for holding said indicator in any position to which it may be moved, and a connection from said plate to said retaining-lever whereby said indicator is released by movement of said plate.

10 17. In a cash-register of the class described, the combination with value-keys registering and indicating mechanisms, of rack-bars for the latter, a locking-frame for said rack-bars and a cam for positively forcing said frame in one of its directions said cam being operated by said keys.

15 18. In a cash-register, a key, a plate having a beveled tooth in line with said key, a normally locked indicator, and means on said plate for unlocking said indicator.

20 19. In a cash-register, a key, a normally locked registering mechanism controlled by said key, two plates adjacent to said key, one of said plates having means for locking said key when depressed and the other having means for engaging the key to unlock the registering mechanism.

25 20. In a cash-register, a key, a plate having a beveled tooth for engagement by said key, an indicator having a number corresponding to the number on the key, a normally locked

actuating device adapted by its movement to operate said indicator, a connection from said plate to the lock of said actuating device, a retaining-lever for holding said indicator in any position to which it may be moved, and a connection from said plate to said retaining-lever whereby said indicator is released by a movement of said plate.

30 21. In a cash-register, a key, a detent for said key, a drawer, means controlled by the drawer for locking said detent, and other means controlled by the drawer for unlocking said detent.

35 22. In a cash-register, a key, a normally inoperative registering mechanism, two members adjacent said key, one of said members having means for locking said key when depressed and the other member being operated by said key to render the registering mechanism operative.

40 In testimony whereof we affix our signatures in the presence of two witnesses.
